UNITED STATES PATENT OFFICE.

WILLIAM E. PRICE, OF WHITE PLAINS, NEW YORK.

MOUNTING FOR LANTERNS.

Application filed September 19, 1924. Serial No. 738,644.

This invention relates to lanterns, and more particularly to mounting means for a group of electrically lighted lanterns for window, display and stage lighting and 5 other like purposes.

An object of the invention is to provide an improved mounting means for a series of electric lighted lanterns grouped in a unit, said mounting means serving as a conduit 10 to enclose the feeder wires.

A further object of the invention is to provide a mounting means for a unit of electrically lighted lanterns in which each individual lantern has an improved simple 15 swivel supporting means wherethrough the conductor wires for the lantern may pass to the lantern.

Another object of the invention is to provide a mounting means of the character described constructed of few and simple parts 20 which are inexpensive to manufacture and which form a neat, efficient and highly practical device for the purposes described.

Other objects of this invention will in part 25 be obvious and in part hereinafter pointed out.

Certain features herein shown and described are shown, described and claimed in my co-pending application, Serial No. 719,- 30 458 filed in the United States Patent Office on the 12th day of June, 1924 and accordingly not claimed herein.

With the above exception, the invention accordingly consists in the features of construction, combinations of elements and arrangement of parts which will be exemplified in the construction hereinafter described and of which the scope of application will be indicated in the following claim.

40 In the accompanying drawing, in which is shown one of the various possible illustrative embodiments of this invention,

Fig. 1 is a perspective view of a group of lanterns forming a lighting unit and having 45 mounting means embodying the invention; and

Fig. 2 is an enlarged view in side elevation corresponding to Fig. 1 with parts broken away to show the interior construction of 50 the swivel mounting and conduit.

Referring in detail to the drawing, 10 indicates a lantern pivotally mounted on a U-shaped bracket 11 which is adjustably and removably secured to the lantern casing 12 55 by means of clamping wing screw 13. The lantern 10 may be of any suitable design but

preferably is of the enclosed type having an opening therein adapted to be fitted with a removable closure whereby the light projecting from said opening may selectively be 60 changed to suit various conditions as is fully described in my co-pending application above referred to.

Each lantern 10 may comprise the casing 12 having a front opening 12^a normally closed by a removable door 14 that is held in place by a pair of resilient, flat, clamping straps 15 each of which is fastened at one end thereof by a screw 15^a to a side of the 65 casing adjacent the pivotal mounting. 70

A socket 16 in which the bulb 17 is secured may be slidably mounted lengthwise of the bottom of casing 12 for adjustment with respect to a lens 14^a in the door 14, or with respect to a reflector 12^b formed in the rear interior side of the casing 12. Suitable means, such as wing screw 18 extending through the casing 12 may be provided for maintaining the bulb 17 in a desired adjusted position. 75

The individual lantern brackets 11 are spaced along a channel supporting frame 20 and are adapted each to have a swivel mounting 19 thereon so as to form a lighting unit, as for example like that illustrated in Fig. 80 85 1. The channel frame 20, together with the lanterns 10 may be supported in any suitable well known manner and is here shown suspended from a pair of spaced inverted stanchions 21 which are pivotally connected 90 at 22 to end angle pieces 25, the latter being firmly secured to the ends of the channel frame 20 by screws 24 as shown in Fig. 1. To permit the swinging adjustment and holding of the unit in various required positions, wing screws 25 are provided at the pivotal connections 22. 95

A dominant feature of the invention is the construction of the swivel mounting 19 which may be preferably formed for simplicity as follows: An anchoring projecting portion 11^a having a central opening or passage 11^b is provided at the junction of arms 11^c forming the sides of the U-bracket 11 and said anchor portion 11^a has its free end 11^d 100 reduced in cross-section or turned down to form a shoulder 11^e. Each end 11^d is inserted in an opening provided in the channel frame 20, and a bearing washer 26 is placed over the end 11^d on the inner side of the 105 channel frame 20. The end 11^d is then peened over to form a flange collar 11^f for 110

clamping the channel frame 20 and washer 26 between the shoulder 11^a and the collar 11^b as shown in Fig. 2, said clamping effect being arranged to permit rotative movement 5 between bracket and frame 20. To permit the above described construction, the anchoring portion 11^a is formed of malleable metal as malleable iron, brass or similar material. The mounting 19 thus formed provides a 10 simple means for pivotally rotating the brackets 11 with the lanterns 10 on channel frame 20. Conductor wires 27 for supplying power to light bulb 17 may be passed from the rear outside of the lantern 10 15 through opening 11^b in the anchoring portion 11^a and connected with feed conductors 28 extending lengthwise the inner side of channel frame 20, a loop 27^a being provided in the exposed portion of the wire 27 to permit 20 free swinging of the lantern 10 on its bracket 11 and swivelling of the latter on the frame 20. Suitable means may be provided to totally inclose the feed conductors 28 in said channel frame 20, as for example a sheet 25 metal cover 29 secured to the side of channel frame 20 by screw 30.

It is apparent from the above description and drawings that the lighting unit may be mounted either overhead, on or below the 30 level of the area to be illuminated, and the lanterns may be independently adjusted to project the light in any direction to obtain various desired lighting effects.

It will thus be seen that there is provided 35 a device in which the several objects of this invention are achieved and which is well

adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense. 40 45

Having thus described my invention, I claim as new and desire to secure by Letters Patent:—

In a lighting unit, a frame member of U-shaped section having a cover portion fitted 50 over the upturned edges thereof to form a conduit, a series of electrically lighted lanterns each supported between the forked arms of a bracket, a swivel mounting for connecting each bracket to the frame member, and feeder conductors carried in said conduit to supply power to the lanterns, said mounting comprising an anchoring projection having its free end portion reduced in 55 cross-section to form a shoulder, and a supporting frame member having an opening therein to receive said reduced end portion to extend through said member, said reduced portion being adapted to be peened over to form a flanged collar for swivelly connecting said bracket and member, said projection having a central opening therethrough 60 communicating with said conduit to permit the passage of conductor wires for connection with the feeder conductors. 65 70

In testimony whereof I affix my signature.
WILLIAM E. PRICE.
